UNITED STATES PATENT OFFICE

HARRY R. MCMAHON, OF CORAOPOLIS, PENNSYLVANIA, ASSIGNOR TO STANDARD STEEL SPRING COMPANY, A CORPORATION OF PENNSYLVANIA

BUMPER CONSTRUCTION

Application filed November 10, 1930, Serial No. 494,536. Renewed June 10, 1931.

This invention relates to a bumper construction and more specifically to the end construction of a bumper.

Bumpers as heretofore known contain recognized defects and the practice has been to accept such defects because of the lack of remedy therefor. These defects include lack of strength and proper yieldability and inefficiency due to accumulation of foreign material or to corrosion from the elements such as rain or snow, or to both such accumulation and corrosion.

I have discovered, however, that these defects can be obviated and hence one object of my invention is to provide a bumper construction which is independent of the elements and which is closed to foreign particles, thus producing a bumper of much greater life and efficiency.

20 A further object of my invention is to simplify a bumper end construction and at the same time produce an unusually strong and attractive bumper which is economical to make and easy to assemble.

25 A further object is to produce a multiple impact bar bumper having cylindrical end portions to which a similar end portion of the rear bar is pivotally secured, while at the same time, allowing for necessary play and 30 flexure of the parts.

35 A still further object is to form the ends of the impact bars of a bumper with correlated cylindrical terminals, having cutaway portions for guiding and limiting a rear bar whose cylindrical terminal fits partly within 40 the terminals of the impact bars.

Other and further objects and advantages will be understood by those skilled in this particular field.

40 I have illustrated one embodiment of my invention in the accompanying drawings wherein:

Figure 1 is a vertical section through such an end construction.

45 Fig. 2 is a perspective view of the end construction of Fig. 1; and

Fig. 3 is a plan view of the bumper as a whole but omitting the connections at the 50 ends.

Similar numerals refer to similar parts throughout the several views.

In the form of the invention shown, there are two impact bars 10, each having a cylindrical terminal or end portion 11 as clearly shown in Fig. 2. These cylindrical portions 11 may be formed in any suitable way not forming a part of the present invention, but however formed they are provided as shown at the inner central corner with a cutaway portion 12, the form of which is clearly apparent from Fig. 2.

The impact bars are assembled so that they are vertically superposed and in practice they may be slightly spaced so that they do not rub upon one another, although they may, if preferred, be in substantial contact. The cylindrical portions 11 are so cutout as at 12 that when they are assembled, the cutout portions are adjacent each other, thereby forming a continuous slot, for a purpose which will be hereinafter explained. This slot, as is clear, is bounded top and bottom by the shoulders 13 which act as limiting abutments for the upper and lower edges of the rear bar 14, at the same time limiting the pivotal movement of the rear bar by the vertical portions 13a of the cutaway portions 12.

75 The rear bar 14 has a coiled terminal 15 which is cylindrical also and coiled in the same direction (although not necessarily so) as the portions 11 of bars 10, but the diameter of portion 15 is less than that of portions 11. The dimensions are so adjusted that the maximum external diameter of portion 15 of bar 80 14 is not greater than the minimum internal diameter of portions 11 of bars 10. In practice they may be so dimensioned that a comparatively snug fit is secured which permits 85 relative pivotal movement under impact or stress.

The two bars 10 and bar 14 are assembled as shown in Fig. 2 so that portion 15 of bar 14 extends part way up into portion 11 of upper bar 10 and part way down into portion 11 of lower bar 10, bar 14 itself being disposed centrally relatively to bars 10. A suitable bolt 16 is passed through all the cylindrical portions, and this bolt may have an enlarged head 17 and a washer member 18 100

between the head and the top edge of the portion 11 of top bar 10. The lower end of the bolt is provided with a washer member 19 closing the lower end of cylindrical portion 11 of lower bar 10 and is secured in place by a suitable lock washer 20 and nut 21 which is threaded onto the exteriorly threaded end of bolt 16.

I have, therefore, by the above construction, provided a bumper which attains all the functions and advantages above set forth and which in use has proved to be highly effective and long-lived. The shape of the bumper as a whole is not necessarily that of Fig. 3, which is shown merely by way of example, but may be any suitable or preferred design depending upon the particular usage and conditions which must be met. The rear bar 14 is, of course, suitably connected to the appropriate portions of the vehicle to which the bumper is to be attached, and may, if desired, be connected as at 22 to the impact bars 10, but this forms no part of the present invention.

While I have shown bars which have a straight cross section, I may, however, use bars formed on the arc of a curve without departing from the principles hereinabove set forth. Other modifications, variations, substitutions and omissions may be likewise made as required when such are within the terms of the present invention wherever they utilize the principles and advantages of the present bumper.

What I claim as new and desire to secure by Letters Patent is:

1. In a bumper; a plurality of impact bars having superposed hollow terminals and a rear bar centrally disposed relatively thereto and having its terminals within the hollow terminals of the impact bars.

2. In a bumper construction, a plurality of impact bars having superposed hollow cylindrical terminals and a central rear bar having a similar terminal fitting partly into each of said impact bar terminals.

3. In a bumper construction, a plurality of impact bars having superposed hollow cylindrical terminals and a central rear bar having a similar terminal fitting partly into each of said impact bar terminals, which are cut away for guiding and limiting said rear bar.

4. In a bumper construction, a plurality of impact bars having superposed hollow cylindrical terminals and a central rear bar having a similar terminal fitting partly into each of said impact bar terminals, which are of greater diameter than the terminals of said rear bar.

5. In a bumper construction, a plurality of impact bars having superposed hollow cylindrical terminals and a central rear bar having a similar terminal fitting partly into each of said impact bar terminals, which have a

minimum internal diameter not less than the maximum external diameter of the terminal of said rear bar.

6. In a bumper construction, a plurality of impact bars having superposed hollow cylindrical terminals and a central rear bar having a similar terminal fitting partly into each of said impact bar terminals, which are cut away to a predetermined extent at the central inner corners to form abutments for the upper and lower edges of said rear bar and a guiding and limiting slot for the bar itself.

7. A bumper end construction formed by two associated partly cutaway cylindrical portions on the ends of bumper impact bars and a cylindrical portion of an associated rear bar received partly within each and means for securing said cylindrical portions together in such positions.

8. A bumper end construction formed by two oppositely associated partly cutaway cylindrical portions on the ends of bumper impact bars and a cylindrical portion of an associated rear bar pivotally positioned partly within each of said former portions, the rear bar being guided and limited in its movements by said cutaways, the whole being secured in operative association by a bolt assembly.

9. In a bumper, a plurality of impact bars having adjacent terminals configured so as to receive within themselves portions of the terminals of an operatively associated rear bar, and a rear bar disposed relatively centrally of said impact bars and having its terminals secured partly within the adjacent impact bar terminals as aforesaid.

10. In a bumper, a plurality of impact bars having their terminals contiguous and so configured as together to receive the terminals of an associated rear bar, and a rear bar operatively disposed with respect to said impact bars and having its terminals arranged as aforesaid.

11. A bumper end construction comprising a plurality of impact bars having superposed terminals so configured as together to receive the terminal of an operatively associated rear bar, and a rear bar having a terminal so disposed.

12. A bumper end construction comprising a plurality of impact bars having terminals constructed and arranged to form together a generally tubular structure, having a slot, and a rear bar extending through said slot and having its terminal in said structure.

13. A bumper end construction comprising a plurality of impact bars having terminals constructed and arranged to form together a generally tubular structure, having a slot, and a rear bar extending through said slot and having its terminal in said structure, and means for pivotally securing the same in such positions.

14. A bumper end construction comprising

a generally tubular structure made up of adjacent ends of impact bars, and a rear bar having its terminal in said tubular structure.

5 15. In a bumper joint, two cylinders as the termini of a pair of impact bars, and a rear bar having a terminal received by said cylinders.

10 16. In a bumper joint, two superposed cylinders as the termini of a pair of parallel impact bars, and a rear bar operatively associated with said impact bars and having a terminal received by said cylinders.

15 17. In a bumper joint, two superposed cylinders as the termini of a pair of parallel impact bars, and a rear bar operatively associated with said impact bars and having a terminal received by said cylinders, which latter are provided with a slot, through which said rear bar extends.

20 18. In a bumper joint, two superposed cylinders as the termini of a pair of parallel impact bars, and a rear bar operatively associated with said impact bars and having a terminal received by said cylinders, which latter are provided with a slot, through which said rear bar extends, said slot lying partly in each cylinder.

25 19. In a bumper joint, two superposed cylinders as the termini of a pair of parallel impact bars, and a rear bar operatively associated with said impact bars and having a terminal received by said cylinders, which latter are provided with a slot, through which said rear bar extends, said slot lying partly in each cylinder, and being less in extent than the combined height of the cylinders.

30 20. In a bumper joint, two superposed cylinders as the termini of a pair of parallel impact bars, and a rear bar operatively associated with said impact bars and having a terminal received by said cylinders, which latter are provided with a slot, through which said rear bar extends, said slot lying partly in each cylinder, and being less in extent than the combined height of the cylinders, and forming a mechanical guide for said rear bar.

35 In testimony whereof, I have hereunto subscribed my name this 6th day of November, 1930.

50 HARRY R. McMAHON.
